UNITED STATES PATENT OFFICE.

GEORGE H. BLACK, OF BUCHANAN, MICHIGAN, ASSIGNOR OF ONE-HALF TO
DAVID W. PIERCE, OF SAME PLACE.

HAND-CULTIVATOR.

SPECIFICATION forming part of Letters Patent No. 349,561, dated September 21, 1886.

Application filed March 29, 1886. Serial No. 196,969. (No model.)

To all whom it may concern:

Be it known that I, GEORGE H. BLACK, a citizen of the United States, residing at Buchanan, in the county of Berrien and State of Michigan, have invented certain new and useful Improvements in Hand-Cultivators; and I do declare the following to be a full, clear, and exact description of the invention, such as will enable others skilled in the art to 5 to which it appertains to make and use the same, reference being had to the accompanying drawings, and to letters or figures of reference marked thereon, which form a part of this specification.

15 Figure 1 of the drawings is a representation of this invention, and is a perspective view. Figs. 2, 3, and 4 are detail perspective views.

This invention has relation to hand-cultivators; and it consists in the construction and 20 novel combination of parts, as hereinafter set forth, and pointed out in the claim.

In the accompanying drawings, the letter A designates the transverse wooden handle, and B B are the iron shaft-bars, which are 25 connected at their forward and lower ends by the journal-bolt a, on which the supporting-wheel C revolves. These shaft-irons are flattened from side to side, and extend backward parallel to each other and at a low angle of inclination from the journal a to the 30 bends b, where the irons diverge gradually as they extend upward and rearward at a higher angle of inclination. When in use, the lower portions of the shaft-irons are level, or 35 nearly so. At their upper ends the shaft-irons are provided with lateral flanges c, which are perforated for the passage of the bolts d, whereby they are secured to the under side of the handle, the latter also being provided 40 with perforations for the reception of the fastening-bolts. These perforations are made through the square bearing-faces e, which are formed on the under side of the handle, the main portions of which are, however, turned 45 round in order to facilitate handling.

Just below the bends b of the shaft-irons are made in the same the perforations g and h, which are about three inches apart in each iron, being designed for the passage of the

transverse bolts k, which also pass through 50 the blocks D D and the inclined upper portion, E, of the standard F, said portion projecting forward and downward at the same inclination with that of the lower portions of the shaft-irons. The blocks D D are located 55 inside the shaft-irons, one on each side of the portion E of the standard, which is closely embraced between them, and securely fastened thereto and to the shaft-irons by the bolts k k. From the portion E the standard F 60 extends in curved form downward and backward, and thence forward and downward, its lower end having the proper inclination to give the shovel the proper slant, and being provided with perforations l l, for the bolts 65 which secure the shovel-sleeve G thereto.

The wheel C is of steel, being usually made with steel-wire spokes and with a steel hoop, the hub being of proper size to fit between the 70 shaft-irons.

The wooden blocks D D act as washers to hold the iron shovel-standard F in central position, so that it will follow the wheel truly, and at the same time these blocks serve to spread the shaft-irons and hold them firmly at 75 the proper distance apart for the hub to work easily and truly between them.

The shovel-sleeve G is designed to embrace 70 the lower end of the standard, and is provided with perforations for the fastening-bolts. 80 Its lower portion is recessed in concave form from side to side to receive the shovel-back H, to which is attached the shovel K by the bolt m. The shovel-back is adjustable in the concave of the sleeve to enable the shovel to be 85 adjusted as desired.

The shovel K is made long—about sixteen 90 inches in length—and is formed at one end with a common shovel, and at the other end it is made in bull-tongue shape.

Having described this invention, what I claim, and desire to secure by Letters Patent, is—

The improved hand-cultivator herein described, consisting of the bent shaft-irons 95 parallel in their lower portions and diverging in their upper portions, which are inclined at a higher angle than said lower por-

tions, and provided with lateral end flanges, the wooden handle secured to the said flanges, the wooden washer-blocks interposed between the bases of the diverging portions of the shaft-
5 irons, the standard secured between the washer-blocks, and the wheel journaled between the outer ends of the parallel shaft-irons, substantially as specified.

In testimony whereof I affix my signature in presence of two witnesses.

GEO. H. BLACK.
